LIFE SAVING APPARATUS FOR AVIATORS

Application filed October 14, 1929. Serial No. 399,570.

Our invention relates to new and useful life saving apparatus to be worn by aviators and passengers in air craft, enabling them, in cases of crashes over water, to maintain normal respiration until such a time as they can disengage themselves from the wreckage and rise to the surface.

The invention also affords protection from drowning of persons who may be entrapped in aeroplanes, which, through accident, may fall and sink under the surface of the water, until the craft can be raised to the surface or until the persons are extricated from the entangled wreckage either with or without assistance from the surface, by affording a means of respiration during their submergence and providing a buoyant device whereby, after extrication, they may ascend to the surface and remain afloat. The apparatus also permits normal respiration to be maintained by wearers who, through accident or intent, may be required to abandon aeroplanes over water, by parachute, which in landing in water, frequently enfolds and entangles the person to such an extent as to endanger his life until he disengages himself from the entanglement and casts off the parachute harness.

The illustrated and preferred embodiment of the invention is applicable to submergence with and emergence from crashing and sinking aeroplanes and enfolding parachutes or to entrance and stays in spaces filled with toxic or vitiated air as over battle fields or to descents and ascents for miscellaneous purposes below the surface of the water. The device can be worn simultaneously with aeroplane parachutes but its satisfactory operation is independent of the parachute irrespective of the open or closed position of the latter.

Before describing the apparatus the conditions attendant on accidental crashing of aircraft on the water and their sinking below the surface will be briefly stated. Aircraft, especially the types that are designed to ascend from or land upon the surface of the water, or to be launched from catapults or from long runways aboard ship, have difficulty at times in attaining the velocity necessary

for successful ascent; also in rough seas, or from other causes, such craft in attempting to land upon the surface of the water sometimes damage their pontoons; causing them to fill with water. Under such conditions the planes will become over-balanced and tip forward, nosing under the water, and sinking before the pilot, crew and passengers can extricate themselves from the planes. Also, there are frequent cases in which aircraft accidentally fall from more or less great heights, when operating over water, the craft frequently being wrecked as it plunges beneath the surface of the water.

It is well known that under the above mentioned conditions, the force of the impact of a plane on the water may be of such as to cause the wings to collapse and cover the cockpit, and prevent egress from the cockpit until such time as the wings have been removed or an opening made through the fabric. Also under such conditions the fittings, struts and wire controls are very likely to become damaged and disarranged, entangling the occupants below the surface. The frequent fatalities that have already occurred from such causes are indicative of the improbability of the sustenance of life of the occupants sufficiently long to enable rescue from the surface, or to extricate themselves and rise to the surface unless they are equipped with apparatus which will adequately fulfill their respiratory requirements under the varying pressure conditions of descent into the water or when remaining under water at a stationary depth; maintain normal respiration under water while disentangling themselves from wreckage; maintain normal respiration while ascending to the surface and provide a means of remaining afloat without physical exertion of swimming after reaching the surface.

Aside from providing a means of respiration under the conditions mentioned above, the practicability of a device for this purpose is contingent upon its lightness in weight, compactness, and simplicity of operation and its ability to be worn over the flying clothing of aviators or aircraft passengers; to be worn over the flying clothing simultaneously with

the parachute in its closed position as well as its open position when the occupants abandon the craft in mid-air and to be worn without interference with the movements of the pilot, crew and passengers in the performance of their various duties attendant on the operation of the craft and its controlling equipment. Heretofore, there has been no known development of a device that will fulfill

10 fill these requirements and our device will.

The wearer may supply himself with respiratory air when submerged in water and maintain the supply at the rate required to maintain equalization of pressure within the 15 apparatus and the wearer's body and the increasing water pressure attendant on descent of the craft through the water and to maintain this equilibrium of internal and external pressures after the plane comes to rest on the 20 bottom.

The device provides a sufficient quantity of respiratory air to maintain life of persons submerged in water over prolonged periods in fallen aircraft, without encumbering the 25 wearer with the excessive weight of the large respiratory air containers which would otherwise be required.

The apparatus may be worn independently or simultaneously with an aircraft parachute without interference with the functions of either and at the same time provide a means whereby the wearer may inflate the reservoir with a respirable supply of air during his descent through the air, and maintain 35 his normal respiration even though he may be enveloped by the parachute or entangled in its harness after landing in water.

The device is buoyant, will support the body of a parachute operator, when landing 40 in water, and hold his head out of the water in cases where he is entangled in the parachute harness and the parachute is carried along the surface for considerable distances and at varying speeds by the wind.

45 The wearer may also be supplied with respiratory air in such manner that normal respiration is safely maintained regardless of the surrounding abnormal and varying conditions of external pressure to which he is 50 subjected.

The device will also supply means for normal respiration for occupants of aircraft at altitudes where low external pressures otherwise prevent normal respiration.

55 In conjunction with fireproof clothing, the device will furnish a respiratory supply of air to persons who may be occupants of aircraft burning in mid-air or who may become entangled in the wreckage of burning 60 and fallen aircraft, until they can be extricated.

The device is small, light and easily-adjusted, can be easily operated by inexperienced persons and will supply them with 65 respirable air for entrance into spaces containing toxic, obnoxious gases or vitiated air.

The apparatus will also furnish a respirable supply of air to persons in descending, and staying for certain periods under water and ascending without outside assistance to the surface such as may be required for miscellaneous diving work.

70 Referring to the drawings, in which like parts are similarly designed:

75 Figure 1 is an elevation, partly in section of the device;

Fig. 2 is an enlarged section of the chemical container;

Fig. 3 is a vertical section on line 3—3 of 80 Fig. 1;

Fig. 4 is a vertical section of the snap valve;

Fig. 5 is a vertical section on line 5—5 of 85 Fig. 4.

The apparatus consists of a broad belt consisting of an inflatable bag made in two sections 1 and 2. Section 1 is a reservoir for exhaled air and for a supply for a short period of pure air or oxygen obtained from an oxygen or compressed air flask 3. Section 2 is a reservoir from which the wearer is supplied with pure or respirable air for sustained respiration under all conditions.

An air oxygen or compressed air inlet 4 is provided with a check valve whereby a respirable supply of gas may be obtained from an extraneous source such as the oxygen flasks forming part of the high altitude apparatus with which airplanes are provided. Both sections are provided with bellows, 90 walled bottoms as indicated in dotted lines, Fig. 1. Section 1 contains a canister or container 5 for holding a chemical which absorbs CO₂. Sections 1 and 2 are connected together at the canister nozzle 6 which pass

95 through a web of rubber or rubber fabric web 80 connecting the two portions 1 and 2. At the canister end of section 1 there is an offset or depression 7 the purpose of which will be

100 described later in connection with the canister and its operation. Sections 1 and 2 when connected form a continuous inflatable reservoir the ends of which are provided with loops or buckles 8, or straps 9 which permit adjustment of the belt around the body of 105 the wearer. Between the ends of the belt, the top is extended upwardly at 10 at the back of the belt. Likewise and near each end of each section of the belt at the top are shorter vertical extensions 11 and 12 as 110 shown. Each of these parts 10, 11, and 12 form an integral inflatable part of the apparatus. Near the middle of the belt on the lower portion is a strap 13, one end of which is permanently attached to an eye 14 on the bottom of the belt below part 10. This strap

115 carries an adjustable buckle or loop 15 that has two short chains 16, 17 provided with snap hooks 18 and 19 respectively for engagement with loops 20 and 21 respectively.

After fastening the device about the body by strap 9, this strap 13 is brought between the legs and adjusted along the strap in front of the belt, and hooks 18 and 19, engage 5 in the loops 20, 21. The strap 13 is fastened with a certain amount of slack and its purpose is to prevent the apparatus rising over the wearer's head when he lands in water. Under this condition the apparatus due to 10 its buoyancy rises up a certain distance on the body, part 10 assuming a position back of the wearer's neck. Parts 11 and 12 assume a corresponding position in the front of the wearer bringing these shorter extensions 15 close to the mouth, providing a sufficient buoyancy high on the body so as to give a well balanced support to the body of the wearer and keep it in an upright position without interfering with the movement 20 of the arms. Part 10 projects upwardly to a greater extent than parts 11 and 12 and has the additional function of supporting the neck of the wearer at the back thus preventing his head from submerging in cases 25 where he may be pulled along the surface rapidly by a wind filled parachute. The canister 5 holding the chemical which absorbs carbon dioxide consists of a light metal box constructed so as to permit an easy flow of 30 air from portion 1 to portion 2 and a high degree of purification of the exhaled air before being inhaled again.

This canister Fig. 2, is placed within the portion 1 above depression 7 and secured to 35 the top of one end of portion 1 by a clamping plate 22 and screws 23 passing through the plate, the fabric of portion 1 into the imperforate top wall 24 of the canister. The two side walls are also imperforate. De- 40 pending from the top 24 of the canister is an imperforate end wall 25 and the opposite end wall 26 is provided with an outlet nozzle 6 that is the sole gas passage between the two portions 1 and 2.

Spaced from this wall 26 is a second wall 45 27 extending upwardly beyond the line of nozzle 6 nearly to the top 24 and also extending below the nozzle to form a trap 28. The bottom of the chamber between the walls 50 25 and 27 is formed by a screen 29 and a screen 30 extends from the top of wall 30 to the opposite wall 25 forming a conduit 31 extending across the top and down one end of the canister to the nozzle 6 and strap 28. The respired air purifying chemical is contained in the chamber between the upper and lower screens 31 and 29 and the imperforate walls 25 and 27. Chemical is supplied to this chamber through an opening closed by a 55 screw plug 32, Fig. 1. Spaced from the vertical wall 25 and the bottom 29 of the chemical chamber is a screen 33 supported by and prevented from collapsing by metal spacing strips 34. The construction is such that no 60 air can pass from one compartment to the other without having first to pass through the chemical. The inhalation compartment 2 is provided with a spring 34 preferably oval in section, one end of which is soldered or otherwise secured to the side of the inhalation tube nipple 35 and the other end soldered or hooked through a hole 36 to the chemical container nozzle 6. The purpose of this spring no matter what its shape is to keep the inhalation reservoir 2 from collapsing 65 over the container nozzle 6 and inhalation nipple 35 and prevent interference with the proper flow of air. The depression 7 in the bottom of compartment 1 promotes the free flow of air through the canister by reason of not having a bellows wall on its bottom.

Compartment 1 is provided with an oxygen inlet 37 connected by a flexible tube 38 to the bottle 3 for oxygen or compressed air in a friction pocket, the bottle being provided with a suitable hand valve 39. The friction pocket is provided with a zipper closure 40 to facilitate the exchange of the bottle 3. Compartment 1 in the location shown is also provided with relief valve 41 designed to maintain a certain excess pressure within the entire apparatus over the pressure of the surrounding medium, irrespective of whether this medium is low or high altitude air pressure, or shallow or deep water pressure. The valve 4 on the inhalation chamber is for the connection to an extraneous source of respirable air such as can be obtained from the large oxygen flasks forming a part of high altitude respiratory apparatus carried in airplanes and other aircraft. Utilization of such extraneous source of air may become necessary in cases where occupants of fallen planes are submerged beneath the water for prolonged periods.

We provide the usual oxygen tube leading from the oxygen flasks carried by the flying machine with a nozzle device 41 Fig. 4, having a bore 42 for the oxygen from the bottle, and a second parallel bore 43. A screw valve 44 controls a passage 45 between the two bores and determines the constant flow of oxygen to the compartment 2. A second spring closed push valve 46 permits a temporary increase of the supply oxygen from bore 42 to bore 43.

The nozzle device is screwed to a head 47 containing a valve 48 provided with a rubber seat 49 held in place by a tubular extension or guide apron 50. The valve structure 4 is the usual spring closed tire inflating valve externally threaded at 51 having a stem 52 extending above or to the top of its casing. This valve casing is screwed at its lower end into a screw plug or thimble 53 that screws into a ring 54 secured to the flexible wall of compartment 2 by a clamping ring 55 and screws 56. A lock nut 57 holds the valve tight and permits its adjustment into and out of the bag.

Seated on this washer is a loose ring 58 and above it a nut or a soft washer 59. Pivoted to ring 58 is a bail 60 carrying a roller 61 that rides on a cam surface 62 on the head 6. 47. This portion of the head projects sufficiently far to the front of the bail to act as an abutment for the arms of the bail when in the position shown in Fig. 4 to prevent the head rotating too far without moving 10 the bail with it and cause release of the bail. The head is pushed over the valve with the apron 50 resting on 59. Valve 48 strikes the upper end of the tubular casing of valve 4, is opened thereby and at the same time 15 valve 48 strikes the upper end of stem 52 and opens valve 4. Bail 60 is swung over the cam surface 62 and latches the head in place, while permitting a swivelling action of the head with respect to the inhalation 20 compartment 2. By this means the aviator is supplied with oxygen from the supply in the air craft, through the compartment 2, and inhalation tube. By simply pushing the bail over the cam surface the connection is automatically released and both valves 4 and 48 25 close.

Parts 10, 11 and 12 are provided with metal loops 64, 65, 66 and 67. Shoulder straps 68 and 69 are fastened to loops 64 and 65 that 30 respectively connect with buckles 70 and 71 connected to the loops 66 and 67. These shoulder straps are located so as to distribute the weight of the apparatus, in such a way that there is no "warping" or "distortion" of 35 the apparatus when worn nor interference with the movements of the arms of the wearer. The position of the oxygen bottle 3 when the device is adjusted is under the right arm at the waist line. The chemical 40 container is in a similar position under the left arm. The inlet check valve 4 is near the front of the body to be readily accessible for connecting to an extraneous source of respiratory gas.

45 The metal breathing valve 72 of the usual type is connected to flexible breathing tubes, 63 for the inhalation portion 2 and 73 for the exhalation portion 1. The rubber mouthpiece A connects to the tubular connection of 50 the breathing valve 72 provided with a cut-off valve 74. This mouth piece A has a rubber mouth closing plate 75 having an extension 76 passing under the chin, a plate 77 for resting against the teeth, between the teeth 55 and lips, and lugs 78 to be grasped between the teeth.

The occupants of the aircraft, while preparing themselves for flight and before entering the aircraft, adjust the apparatus on 60 the body over the clothing. The parachute is then put on in the regular manner, over the apparatus, hooking the breast strap of the 65 parachute in such a manner that the mouthpiece and breathing tubes 63 and 73 of the breathing apparatus will be left free. The

shut-off valve 74 is normally closed until the mouthpiece A is placed in the mouth. The exhalation compartment 1 of the apparatus contains a relief valve 41 which permits the reservoir to remain inflated at a pressure 70 slightly in excess of the pressure of the surrounding medium irrespective of whether the medium is atmosphere at high or low altitudes or deep or shallow water. Normally, for aircraft use, the apparatus is inflated 75 through nozzle 41* from a compressed air or oxygen flask installed in the plane and forming a part of the present type of altitude equipment. Normal inflation of the apparatus makes it immediately available at all 80 times for use as a life preserver without any additional adjustment.

Inflation in this respect is performed by the wearer after entering the aircraft and before "taking off" by connecting the valve 85 4 with the oxygen supply through nozzle 41. The apparatus is quickly inflated by momentarily pressing down upon the valve 46.

In case of the aircraft crashing into the water the mouthpiece A of the apparatus is placed by the wearer into his mouth and the plug stop valve 44 is now adjusted. This valve 44 is designed to permit regulable flow of oxygen to the apparatus from the oxygen flask in the plane, sufficient to meet normal 90 respiratory requirements or in other words the rate of flow is equivalent to the rate of oxygen absorption by the body. In case it is necessary to abandon the plane by parachute, bail 60 is thrown over and the oxygen supply through the nozzle is cut-off, and the head 95 47 is at the same time pulled off of valve 4. If the craft sinks, after landing on the surface of the water, additional pressure will be required within the apparatus to equalize the 100 increasing surrounding water pressures. Under such conditions compensating pressures within the apparatus may be obtained by opening valve 39 to increase the pressure.

Over inflation of the apparatus under any 110 conditions, in either ascent or descent in water or at atmospheric pressure, or less than atmospheric, is prevented by the relief valve 41 which "spills" the excess pressure within the apparatus.

In cases of abandoning aircraft by parachute, persons descending over water would not be immersed as the original inflation of the apparatus makes it a buoyant appliance which will support them on the surface of the water. In cases where they are submerged for a short distance on impact with the water the necessary inflation to meet the momentary increased water pressure is produced 120 by turning on the valve 39 of the small oxygen flask 3.

For respiratory requirements at high altitudes, the apparatus is connected to the oxygen flask in the plane by means of the head 125 and bail previously referred to and valve 44 130

opened. This same procedure would offer protection against toxic gases such as may be encountered by aviators in gas warfare.

We claim—

- 5 1. A life saving device comprising a body encircling inflatable reservoir having two inflatable compartments of different lengths, one of said compartments having an upward extension for supporting the body of the 10 wearer upright a shorter upward extension at one end and the other compartment having a like shorter extension, said shorter extensions combining to balance tipping action of the longer extensions, an air purifying 15 chamber forming a connection between the two compartments and a breathing tube connected to each compartment.
- 2. A life saving apparatus comprising a body encircling inflatable reservoir having 20 two separated sections an air purifying device in one of said sections and connecting the interiors of said sections, an inhalation tube connected to one section and an exhalation tube connected to the other section.
- 25 3. In a life saving apparatus, an expandable and collapsible inhalation compartment, a chemical containing canister for purifying respiration air connected to said compartment, an inhalation tube connected to said compartment and an open spiral between the canister and tube within the compartment to maintain breathing passage between the canister and tube under all conditions of operation.
- 30 4. In a life saving apparatus two compartments having bellows bottoms, an air purifying canister connecting the compartments and arranged in one of them, said compartment having a non-bellowsed portion at the bottom below the canister.
- 35 5. In a life saving apparatus having two compartments an air purifying canister in one compartment and connected to the other compartment, the latter compartment having a bellows bottom and the former compartment having its bottom depressed below the canister and the remaining portion of its bottom bellowsed.
- 40 6. In a life saving apparatus, two collapsible compartments, an air purifying canister in one compartment and having a discharge neck connecting the compartments, means in the canister for purifying air and a trap below and adjacent to said neck to receive chemical dust from the stream of 45 purified air passing to the neck.
- 55 7. In a life saving apparatus, a flexible

exhalation compartment, a canister therein having a discharge neck, an inhalation compartment connected to said neck and a flexible web between the compartments connecting them together.

8. A life saving apparatus comprising an inflatable compartment having an upward extension near one end and a shorter upward compartment at the other, a canister in the compartment at the end opposite the shorter extension, a second inflatable compartment connected to the canister, means for fastening the free ends of the two shorter extensions together in front of the wearer, an oxygen bottle detachably connected to the first compartment, said bottle arranged to be located under one arm of the wearer and the canister arranged to be positioned under the other arm, shoulder straps between longer and shorter extensions, a holding down strap at the bottom of the apparatus.

9. In a life saving apparatus, a flexible exhalation compartment, a canister therein having a discharge neck, an inhalation compartment connected to said neck, means insuring a breathing passage to and from said canister and means for supplying an operator with respirable atmosphere from the apparatus.

10. In a life saving apparatus, two compartments having bellows bottoms, an air purifying canister in one compartment connecting the compartments, a non-bellowsed bottom below said canister and means for equalizing the internal pressure in the apparatus to correspond to the pressure of the surrounding medium.

11. In a life saving apparatus, two collapsible individual sections, an air purifying canister in one of said sections having a neck connecting the sections, and means adapted to prevent the collapsible sections from obstructing the operation of said canister in purifying air for an operator.

12. A life saving apparatus comprising an inflatable reservoir having two separated compartments, an air purifying device in one of said compartments and connecting the interiors of said compartments, an inhalation tube connected to one compartment, and an exhalation tube connected to the other compartment.

In testimony that we claim the foregoing as our invention, we have signed our names.

CLARENCE LOUIS TIBBALS.

FRANK MILLARD HOBSON.
